APPARATUS FOR SHIFTING HANKS OF YARN IN DYEING.

1,202,061.

Specification of Letters Patent.

Patented Oct. 24, 1916.

Application filed October 10, 1913. Serial No. 794,461.

To all whom it may concern:

Be it known that I, PAUL HAHN, a citizen of the German Empire, and residing at Niederlahnstein - on - the - Rhine, Germany, 5 have invented certain new and useful Improvements in Apparatus for Shifting Hanks of Yarn in Dyeing, of which the following is a specification.

The subject-matter of this invention is 10 an improvement in apparatus for shifting hanks of yarn when dyeing.

The improvement consists in incorporating 15 with the machine a regulating mechanism which enables such an adjustment to be made before the machine is started that the beginning of the period at which the hanks must be turned and displaced on their carriers can be regulated relatively to the intermediate period during which the hanks 20 are only displaced, such regulation being varied according to the particular nature or qualities of the yarn to be treated and of the dye employed. The said regulating mechanism therefore enables changes in the control 25 of the operation of the machine to be automatically carried out, which, in other machines can be carried out only by the operator. Such automatic control provides that between a predetermined number of 30 displacements of the hanks from one predetermined part of the dyeing trough to another, the hanks can, at a predetermined period, be also turned on their appertaining carriers.

35 The apparatus according to the present invention comprises a control-device, pivoted to the machine casing, consisting of a control-sector, a pawl, and a pawl-carrying sector, and capable of being preliminarily adjusted before the machine is started; this control-device is automatically adjusted to another control position each time a lever, which is mounted on the machine, strikes against one of two adjustable stops which 40 limit the travel of the machine, and thereby reverses the motion of the machine; a control-mechanism is also provided which contacts with the said control-device and couples the axle carrying the pair of levers for turning 45 the yarn-carrier to a driving system which can provisionally impart to said pair of levers an oscillatory motion and is continuously driven; when the reversal of the motion of the machine occurs this controlling mechanism does not allow said driving 50 system to influence, and impart such oscillating motion to, this pair of levers until, in accordance with that number of displacements of the said control-device which is predetermined by the preliminary adjustment, this control-device obtains a position in which it can disengage a set of detent-members and so cause the said driving-system to be coupled to the said axle, whereby the yarn is not only displaced but simultaneously turned. Further, after the completion of this combined movement, a releasing mechanism which, in the position now occupied by the control-device, is influenced by the stroke of the stop-actuated 60 lever, returns the said control-device to its initial position.

65 One illustrative embodiment of the invention is represented by way of example in the accompanying drawing, wherein:—

70 Figure 1 is a diagrammatic view of a machine of this character provided with the new regulating mechanism; Fig. 2 is a front elevation, partly in section, showing the said mechanism; Fig. 3 is a sectional elevation 75 of the parts of the mechanism which are located at the rear of the machine-casing, the section being taken immediately behind the casing; Fig. 4 is a plan of some parts of the mechanism shown in Fig. 2, and Figs. 80 5, 6 and 7 are detail views.

Figure 1 is a diagrammatic view of a machine of this character provided with the new regulating mechanism; Fig. 2 is a front elevation, partly in section, showing the said mechanism; Fig. 3 is a sectional elevation 85 of the parts of the mechanism which are located at the rear of the machine-casing, the section being taken immediately behind the casing; Fig. 4 is a plan of some parts of the mechanism shown in Fig. 2, and Figs. 80 5, 6 and 7 are detail views.

90 Referring to the drawing, on the front side of the machine-casing 1, in which the driving motor is mounted, is arranged a rear sector 3 (Fig. 6) which is keyed on an axle 2 passing through the said casing and which is provided with a lug 16 directed toward the casing 1. A pawl or latch 4 is pivotally connected to this sector, which also has a shoulder 5 with, at diametrically opposite points, 95 two recesses 6, 7 of corresponding form. Freely rotatable on the sector 3 is a front sector 10^b, its portion 8 being cylindrical, and its portion 9 toothed and weighted by means of a thickened part 11. The portion 100 8 of the front sector 10^b has a projection or lug 12 and a recess 10^a. When this sector rotates the pin 12 will abut against a check-arm 13 which is freely rotatable about the axle 2, and, by abutting against this arm, this sector is arrested. Owing to a detent 15 pivoted to the casing, the check-arm is held fast by one or other of the teeth on the segment 14^a, and consequently the stroke of the front sector 10^b can be lengthened or shortened. 105 The pawl 4 engages the toothed portion 9 of the sector 10^b, and the weighted portion 11 110

of the latter presses on it, so that the engagement is so stable that external vibration will not cause disengagement. Moreover the stability of this engagement during the movements of the sector 10^b is also insured because a lug 20 on the pawl can run on that outer face 19^a of a lever 15^a which is curved and concentric with the axle 2. The said lever 15^a is pivoted at 18 to the casing 1, runs out at its upper end into an abutment-face 21 and has a detent 17 which engages in the toothing 9 and so prevents undesired motion thereof.

On the front end of a second axle 22 (Figs. 2 and 4) which passes through the casing 1 is mounted an angle-lever 23, 24, to the arm 24 of which are pivoted at 25 two levers 26^b, 27^b. As seen in Fig. 4, lever 26^b is forked and has two arms 28, 29, of which the arm 28 has not only a lug 130 normally running on the periphery of the cylindrical portion 8 of the sector 10^b, but also a lug or projection 131 having a form corresponding to that of the recess 7 in the sector 3, while the arm 29 runs out into a finger. The lever 27^b likewise has at its end a lug 33 which also slides on the cylindrical face 8 of the sector 10^b. A finger 34 is provided on a downward extension of the lever 27^b. As Fig. 2 shows, the lever 27^b has also a long, bent, downwardly-extending arm 35, the end of which has a lug 36 which, under circumstances to be explained hereinafter, engages in the recess 6 in the sector 3.

35 The finger 34 on the lever 27^b slides (as seen in Fig. 7) on the periphery of a disk 40 which is journaled on a stub-axle 37 on the casing 1 and has evenly spaced elevations 38. A second disk 41 having elevations 39 is also 40 mounted on the axle 37, but is displaced thereon through a peripheral angle corresponding to the length of the elevations 39. Journaled in front of these disks is a ratchet-wheel 42 which is retained by a detent 43 pivoted at 25^a.

A lever 23^a (Fig. 3) similar in form to the arm 23 of the angle-lever 23, 24 is mounted on the axle 22 but at the rear side of the casing. These levers 23, 23^a when moving 50 downward depress the short arms 44 of two detent-levers 46 which are rotatable about the stub-axes 37 or 37^a on the casing, and by such depression disengage the ends of the levers 46 from the hooks 47, 48 (Figs. 2 and 55 3) at the ends of two controlling rods 49, 50 which are connected to the axle 2 by means of elongated holes 45. The hook 47 of the controlling rod 49 (Fig. 2) is also engaged by the lug 16 on the sector 3, and the hook 60 48 of the controlling rod 50 (Fig. 3) is also engaged by a pin 51 of a three-armed rocking lever 52 fast on the axle 2. The rocking lever 52 is influenced by the antifriction roller 53 of a lever 55 which is pivotally connected to the casing at 54, this roller being

acted upon by a spring 53^b. Owing to stops 57^a, 57^b adjustably mounted on the rails 56 (Fig. 1) which serve as the track for the casing 1, the levers 55 and 52 can be alternately shifted to the right or to the left, and hence 70 oscillatory motions can be given to the axle 2 at long intervals.

The controlling rod 50 is linked at 58 to a lever 60 (Figs. 2 and 5) which is pivoted at 59 to the casing and has a downwardly-extending arm 62 which bears, at the oval eye 61 therein, on the collar 63 of a lever-arm 83; this collar is fast on a sleeve 84 freely rotatable about the axle 26. When the rod 50 falls owing to the disengagement 80 of the arm 46 and the pin 51, it depresses the lever 60 until the upper edge of the oval eye 61 rests on the collar 63. Consequently, the lug 65^a of a latch 68, which is pivoted at 66 on a lever 67 fast on the axle 26, bears 85 against an axially more remote portion of the cam-like edge of that portion of the arm 64 which surrounds the eye 61, and therefore causes the shoulder 69 of the latch 68 to engage in the notch 65^a of a coupler 65 fast on the sleeve 84. A spring 70 mounted on the lever 67 and bearing against the back of the latch makes this engagement secure, the consequence of which is that the axle 26 with the turning-hook 25, which is fast 90 thereon gives an oscillatory motion. This is because the arm 83 fast on the sleeve 84 is linked by a rod 31 to the crank 30, continuously rotated by the axle 19. Like the rod 50, so also the rod 49, which is located on the front side of the machine (Fig. 2) and is normally held in its raised position by the arm 46 and the lug 16, is caused to effect a similar series of operations, owing 100 to a lever 60^a pivoted at 59^a, and a link 31 connected to the crank 30, so that, in this case also, the downward movement of the rod 49 results in an oscillatory movement 105 of the turning-hook 25^b. In these oscillatory movements, the turning-hooks 25, 25^b 110 are limited by stop-sectors 80 which are fast on the axles 26, 26^a, and into the notches 81 of which the stop-pins 78 of spring-pressed levers pivoted at 74 snap in and out again.

It will be assumed that when dyeing the 115 yarn it is desired, after displacing the hanks of yarn in the dye five times, that at the sixth displacement the yarn is to be simultaneously turned on its carrier. It will be further assumed that the sector 10^b has at 120 the toothing 9 four teeth x, y, w, z (Fig. 6) and that the machine has an initial position as indicated by C in Fig. 1. The sector 10^b is then in such a position that the pawl 4 engagess behind the second hook tooth y , while the check-arm 13 is retained by the 125 detent 15 which engages behind the lug 14^a; the lug 12 now bears on this check-arm 13. The device then operates as follows:—When the machine moves forward in the direction 130

of the arrow 86, the hanks of yarn are transferred from position B to position A. When at the end of this movement of the machine, the lever 55, which at the beginning of the 5 said movement in the direction of the arrow 86, has the position shown at D (Fig. 1) strikes against the stop 57^a, it is thereby thrown over into the position shown at C (Fig. 1), and the direction of rotation of 10 the driving motor is simultaneously reversed by means not comprised in the present invention. The lever 52 has been rocked over by lever 55, the axle 2 rotated, and, owing to the pawl 4 on the rear sector 3, the front 15 sector 10^b is driven forward one tooth-pitch, and both the pawl 4 and the detent 17 then engage below the tooth *y*. The machine thereupon travels back in the direction of the arrow 87 and transfers the hank-carriers 20 85 from position A to position B. When the last of these carriers has been transferred, the lever 55 strikes against the stop 57^a and is therefore returned to the position shown at D, the motor being simultaneously 25 reversed, and the lever 52 and the axle 2 rocked back to their former positions. The latter movement brings the sector 3 and the pawl 4 back to their former positions, so that the pawl 4 is now located behind the 30 tooth *w*, while the detent 17 is still behind the tooth *y*. This alternate movement of the machine in the direction of the arrow 86 from C to B, and in the direction of the arrow 87 from B to C, is now once more 35 repeated, the pawl 4 being located behind the tooth *z*, and the detent 17 behind the tooth *w* when the machine is at C. When, however, the machine was previously at the 40 position D, the lug 33, which heretofore had been sliding on the circumferential portion 8 of the sector 10^b, slid from this portion of the sector into the recess 10^a, and the curved lever-arm 35 then made a slight downward movement. This movement sufficed, however, to bring the end of the lever 35 into 45 the path of the sector 3, so that when the machine reaches C and the lever 52 and the axle 2 are again rocked and the sector 3 is consequently driven back one tooth-pitch, 50 this sector strikes with its slanting front edge with some force against a corresponding slanted or rounded portion of the end of the lever 35, and consequently, after raising the latter somewhat when passing it causes the 55 lug 36 to enter the recess 6 in the projection 5 (Fig. 2). After the hanks of yarn have been transferred from B to A, and the machine has again traveled to D in the direction of the arrow 86, the lever 55 again 60 strikes against the stop 57^a. Now, however, since the lever-arm 27^b and the rear sector 3 have become coupled owing to the engagement of the lug 36 in the recess 6, a tractive force is exerted on the lever 27^b, *i. e.* a turning moment on the arm 24, and consequently 65

the following movements simultaneously occur:—

1. The sector 10^b is driven one tooth-pitch, the detent 17 engaging behind the tooth *z*.

2. The stop-pin 16 of the sector 3 passes 70 under the hook 47 of the rod 49, this hooked end being in the path of this pin and having an open portion in the direction thereof.

3. The angle-lever 23, 24 and the lever 23^a, together with the axle 22 passing through 75 the casing, are rocked, and the levers 23, 23^a therefore press downwardly. The result is:—

4. The lever 46 moves to the left whereby its free end releases the hook 48 of the rod 50 which, owing to the pin 51 having been 80 withdrawn from engagement with the hook owing to rocking lever 52 having been changed over by the displacement of the arm 55, falls down an amount determined by the play in the slot 45.

The descent of the rod 50 produces, in the manner hereinbefore described, an operative connection between the crank shaft 19 and the axle 26, so that when the machine makes the now ensuing return movement 90 from position D to position C, it not only displaces the hanks of yarn in the trough, but, owing to the action of the hooks 25, turns them on their respective carriers.

When position C is reached, first of all 95 the lever 55, by abutting against the stop 57^a, again presses the pin 51 under the slanted or rounded top portion of the hook 48. The rod 50 is therefore raised and the operative connection between the axle 26 and 100 the shaft 19 is broken. Simultaneously, owing to the lug 36 engaging in the recess 6, and owing to the rotation of the axle 2, the levers 27^b, 28, 29 and 43 connected to this axle are driven forward, and the lug 105 33 consequently presses against the abutment face 21 and forces back the lever 15^a so far to the right that the detent 17 is raised clear of the tooth *z*. The sector 10^b under the influence of the weighted portion 11 now 110 therefore descends until arrested owing to the pin 12 abutting against the check-arm 13. At the same time the pin 16 comes from under the top of the hook 47, while the pawl 115 43 drives the ratchet-wheel 42 so far around the axle 37 that the finger 34 runs on to one of the elevations 39 on the disk 40. The lever 33 is therefore disengaged from the sector 10^a and the downward movement of sector 10^b is thus rendered possible. Owing 120 to the arm 27^b being raised, the lug 36 must also be disengaged from the recess 6, so that with the return of all parts to the first described position, *i. e.* when the machine was 125 at C, the arm 23, which no longer presses on the lug 44 but is inclined somewhat upwardly, causes the free end of the lever 46, owing to the preponderance of weight, to automatically fall under the top of the hook 48. There then follows a complete repeti- 130

tion of the cycle of operations described. If another movement is desired, *e. g.* if the yarn after each third displacement has to be both displaced and turned, the sector 10^c is so adjusted when it is at position C that the pawl 4 first of all engages below the tooth *w*. To correspond with this adjustment the lever 13 must, of course, have been so held fast, owing to the detent 15 10^c engaging behind the tooth 14^a, that the sector 10^b falls back only two tooth-pitches and then stops owing to its lug 12 striking against the check-arm 13. Moreover, a further modified adjustment of these parts is needed 15 if, after each displacement of the hanks of yarn, it is desired that they be both displaced and turned. Still other combinations can be obtained by increasing the number of teeth on the sector 10^b.

20 The provision of two pairs of turning-hooks, as represented in the drawing, is of course not essential; one pair would suffice. The second pair of hooks and the duplicated arrangement of parts associated therewith is however desirable when it is desired to make the initial adjustment with the machine in either position C or D. In the latter case the two-armed lever 28, 29 under that actuation of the arm 29 which is 25 brought about by the second disk 38, 41, is the means for imparting motion to the pair of hooks 25^b in the following manner:— After the machine has traveled from position D to position C and when the last tooth 35 of the sector 10^b has been driven forward in the position C, the lug 131 falls into the recess 7 of the rear sector 3, whereby the rod 49 is released. Then, owing to the lug 130 striking the abutment surface 21 when 40 position D is reached, the various parts are returned to their initial positions.

I claim:—

1. In apparatus for turning hanks of yarn, the combination of a rail, adjustable stops thereon, a carriage adapted to be driven to and fro along the rail, a continuously driven shaft journaled in the carriage, a pair of turning hooks and adjustable means coacting with said stops for operatively connecting said shaft and said hooks only after a predetermined number of to-and-fro movements of the carriage.

2. In apparatus for turning hanks of yarn, the combination of a rail, adjustable stops thereon, a carriage adapted to be driven to and fro along the rail, a continuously driven shaft journaled in the carriage, a pair of turning hooks and initially adjustable means coacting with said stops for operatively connecting said shaft and said hooks only after a predetermined number of to-and-fro movements of the carriage; and means operated by said adjustable means for returning the latter to their initial position.

3. In apparatus for turning hanks of yarn,

the combination of a rail, adjustable stops thereon, a carriage adapted to be driven to and fro along the rail, a continuously driven shaft journaled in the carriage, a pair of turning hooks, a vertical rod slidable in the carriage and initially retained in its raised position, coupling means rendered operative by the descent of said rod for coupling said hooks to said shaft and adjustable means coacting with said stops for releasing said rod only after a predetermined number of to-and-fro movements of the carriage.

4. In apparatus for turning hanks of yarn, the combination of a rail, adjustable stops thereon, a carriage adapted to be driven to and fro along the rail, a continuously driven shaft journaled in the carriage, a pair of turning hooks, a vertical rod slidable in the carriage and initially retained in its raised position, coupling means rendered operative by the descent, and inoperative by the ascent of said rod for coupling said hooks to said shaft and adjustable means coacting with said stops for releasing said rod only after a predetermined number of to-and-fro movements of the carriage; and means operated by said adjustable means for raising said rod.

5. In apparatus for turning hanks of yarn, the combination of a rail, adjustable stops thereon, a carriage adapted to be driven to and fro along the rail, a continuously driven shaft journaled in the carriage, a pair of turning hooks, a detent pivoted to the carriage, coupling means initially held inoperative by said detent for operatively connecting said shaft to said hooks, an initially adjustable sector rotatably mounted on the carriage and having a cam-surface and ratchet toothing, means coacting with said stops for driving said sector, and releasing means actuated by said cam-surface for driving said detent away from said coupling means only after a predetermined movement of the ratchet-toothing.

6. In apparatus for turning hanks of yarn, the combination of a rail, adjustable stops thereon, a carriage adapted to be driven to and fro along the rail, a continuously driven shaft journaled in the carriage, a pair of turning hooks, a detent pivoted to the carriage, coupling means initially held inoperative by said detent for operatively connecting said shaft to said hooks, an initially adjustable sector rotatably mounted on the carriage and having a cam-surface and ratchet toothing, a pawl engaging said toothing and having a lug, means coacting with said stops for driving said pawl, a detent lever pivoted to the carriage, normally engaging said sector and having a guide surface for said lug, and releasing means actuated by said cam-surface for driving said detent away from said coupling means only after a predetermined movement of the ratchet-toothing.

7. In apparatus for turning hanks of yarn, the combination of a rail, adjustable stops thereon, a carriage adapted to be driven to and fro along the rail, a continuously driven shaft journaled in the carriage, a pair of turning hooks, a detent pivoted to the carriage, coupling means initially held inoperative by said detent for operatively connecting said shaft to said hooks, an initially adjustable sector rotatably mounted on the carriage and having a cam-surface and ratchet toothing, a pawl engaging said toothing and having a lug, means coacting with said stops for driving said pawl, a detent lever pivoted to the carriage, normally engaging said sector and having a guide surface for said lug, and releasing means actuated by said cam-surface for driving said detent away from said coupling means only after a predetermined movement of the ratchet toothing, said detent lever being adapted to be driven back from the toothing by said releasing means.
8. In apparatus for turning hanks of yarn, the combination of a rail, adjustable stops thereon, a carriage adapted to be driven to and fro along the rail, a continuously driven shaft journaled in the carriage, a pair of turning hooks, a detent pivoted to the carriage, coupling means initially held inoperative by said detent for operatively connecting said shaft to said hooks, a sector rotatably mounted on the carriage and having a cam-surface and ratchet toothing, an adjustable lever for supporting said sector in its initial position, means coacting with said stops for driving said sector, and releasing means actuated by said cam-surface for driving said detent away from said coupling means only after a movement of said toothing initially determined by said adjustable lever.
9. In apparatus for turning hanks of yarn, the combination of a rail, adjustable stops thereon, a carriage adapted to be driven to and fro along the rail, a continuously driven shaft journaled in the carriage, a rocking lever and a stop-lever journaled in the carriage, the latter lever being adapted to be driven by said stops, a spring-pressed antifriction roller connected to said stop-lever and bearing on said rocking lever, a pair of turning hooks, and adjustable means driven by said rocking lever for operatively connecting said shaft and said hooks only after a predetermined number of to-and-fro movements of the carriage.
10. In apparatus for turning hanks of yarn, the combination of a rail, adjustable stops thereon, a carriage adapted to be driven to and fro along the rail, a continuously driven shaft journaled in the carriage, a pair of turning hooks, a detent pivoted to the carriage, coupling means initially held inoperative by said detent for operatively connecting said shaft to said hooks, an initially adjustable sector rotatably mounted on the carriage and having a cam-surface and ratchet toothing, a pawl engaging said toothing and having a lug, means coacting with said stops for driving said pawl, a detent lever pivoted to the carriage, normally engaging said sector and having a guide surface for said lug, and releasing means actuated by said cam-surface for driving said detent away from said coupling means only after a predetermined movement of the ratchet toothing, said detent lever being adapted to be driven back from the toothing by said releasing means.
11. In apparatus for turning hanks of yarn, the combination of a rail, adjustable stops thereon, a carriage adapted to be driven to and fro along the rail, a continuously driven shaft journaled in the carriage, a pair of turning hooks, a detent pivoted to the carriage, coupling means initially held inoperative by said detent for operatively connecting said shaft to said hooks, an initially adjustable sector rotatably mounted on the carriage and having a cam-surface and ratchet toothing, a two-armed lever pivotally connected to the detent, one arm resting on said cam-surface and the other having an engaging lug, a member having a recess corresponding to said lug, means coacting with said stops for rocking said member, and a pawl pivoted to said member for driving said sector, said cam-surface being adapted after a predetermined movement to allow said two-armed lever to fall and so cause engagement between said lug and recess.
12. In apparatus for turning hanks of yarn, the combination of a rail, adjustable stops thereon, a carriage adapted to be driven along the rail, a continuously driven shaft journaled in the carriage, a rocking lever adapted to reverse the motion of the carriage on the rail and a stop-lever journaled in the carriage, the latter lever being adapted to be driven by said stops, a spring-pressed antifriction roller connected to said stop-lever and bearing on said rocking lever, and adjustable means driven by said rocking lever for operatively connecting said shaft and said hooks only after a predetermined number of to-and-fro movements of the carriage.

In testimony whereof, I affix my signature in the presence of two witnesses.

PAUL HAHN.
